OWEN BROOKE EVANS, OF LANSDOWNE, PENNSYLVANIA, ASSIGNEE TO THE UNITED GAS IMPROVEMENT COMPANY, OF PHILADELPHIA, PENNSYLVANIA, A CORPORATION OF PENNSYLVANIA.

PROCESS OF BURNING SOLID FUEL.

1,267,646.

Specification of Letters Patent. Patented May 28, 1918.

Application filed January 3, 1916. Serial No. 69,730.

To all whom it may concern:

Be it known that I, OWEN BROOKE EVANS, a citizen of the United States, residing at Lansdowne, in the county of Delaware and 5 State of Pennsylvania, have invented a new and useful Process of Burning Solid Fuel, of which the following is a specification.

The process of the present invention is applicable not only to the furnaces of gas 10 producers in which combustion is incomplete and from which gas generated is led away, but also to other furnaces in which combustion is complete.

The principal object of the present invention 15 is to prevent the adherence of clinker to the side wall of the furnace and thereby permit of the easy cleaning of the fire.

In one way of practising the invention a burning fuel bed is fed through a furnace 20 and superposed regions where ash would and would not fuse are created and maintained in the burning fuel bed by appropriate blast control including, if desired, the use of cooling agents. In passing from one of these 25 regions to the other, clinker goes through a temperature zone of solidification and if unconsumed fuel or carbon goes through this zone in admixture or association with the clinker, it prevents the latter from solidifying or agglutinating into large masses, but it does not prevent the clinker in solidifying from adhering to the furnace walls. To prevent the solidifying clinker from adhering to the side wall of the furnace in accordance with the invention, space is provided and maintained between the lateral surface of the fuel bed and the surface of the furnace side wall in the vicinity of the temperature zone of solidification, and this is 35 done by separating the surfaces of the furnace wall and of the fuel bed at the temperature zone of clinker solidification, thus providing against contact between the furnace walls and the lateral surface of the fuel bed, and by appropriately controlling the blast and its application to the fuel bed in order to maintain the temperature zone of clinker solidification at the place where such

separation occurs. Thereafter the carbon or unconsumed fuel which was carried along 50 with the admixture entering the zone or region where the clinker solidifies, may be burned out, thus leaving the clinker in such divided condition that it can be readily removed to clean the fire. 55

Broadly speaking, the invention consists in preventing the adherence of clinker to the walls of the furnace by providing and maintaining space between the surface of the furnace side wall and the surface of the 60 fuel bed in the neighborhood of the temperature zone of solidification of clinker, by passing the solidifying clinker out of contact with the furnace side wall, and the invention also consists in controlling the location of this temperature zone by appropriate blast control and application, the blast being applied either by suction or pressure. 65

The invention will be claimed at the end 70 hereof but will be first described in connection with apparatus suitable for its practice and illustrated in the accompanying drawings in which—

Figure 1, is an elevational view, principally in section, of one type of furnace or 75 producer.

Fig. 2, is a similar view of a generator or furnace of a water gas apparatus.

Fig. 3, is a similar view of another type 80 of a generator or furnace of a water gas apparatus.

Fig. 4, is a similar view illustrating a modification capable of embodiment in a furnace useful in the practice of the invention, and 85

Fig. 5, is a sectional view taken on the line 5—5, of Fig. 4, looking upward.

In the drawings 1, is a furnace, 2, a fuel intake, 3, a grate, and 4, cleaning doors. 5, indicates a region in which ash fuses, and 6, 90 indicates a region in which clinker does not fuse and at the top of which is located a temperature zone of solidification of clinker. At this temperature zone of solidification of clinker, the fuel is passed, fed or made to 95 travel out of contact with the furnace wall,

so that surrounding this zone, space is provided and maintained as at *a*, between the surface *b*, of the fuel bed and the surface *c*, of the furnace wall. One way of doing this is to provide an off-set in the furnace, or bosh, *7*, the purpose of which is to prevent the fuel immediately below from coming into contact with the furnace wall. As shown in Figs. 1 and 2, this temperature zone of solidification of clinker is maintained in the vicinity of the passage of the fuel bed out of contact with the furnace wall by apportioning a divided blast in the fuel bed and in Fig. 3, by changing the direction and application of the gas making fluids.

In Fig. 1, 8 and 9, are air connections, 10 and 11, are connections for steam, products of combustion, cooling agents or the like, and 13, is an offtake for products of combustion, fuel gas, or the like. Air is admitted below the grate through connection 8, additional air being supplied through connection 9, to maintain the high temperature zone 5, steam, products of combustion or the like being admitted through 10 or 11, as required. By properly proportioning the air, steam, cooling agents, products of combustion, or the like, admitted below the grate 3, and below the bosh 7, the temperature of the fuel bed in the bosh is maintained above the solidification temperature of the clinker, and the temperature of the fuel bed in contact with the walls below the bosh 7, is maintained below the solidification point of the clinker, so that the molten clinker flowing through the bosh 7, is solidified while out of contact with the furnace wall and before it again comes into contact with the furnace wall.

Referring to Fig. 2, the process is as above described, and 14 and 15, are air connections, and 16, 17 and 18, are connections for admitting steam, products of combustion or the like. 19, 20 and 21, are valved offtake connections for fuel gas, products of combustion, and the like, which are led from the generator through connection 22. The "blow" consists in admitting air through connections 14 and 15, and discharging the products through the open valve 19, into connection 22. During this period of blow, steam, products of combustion, or the like, may be admitted through valve 16 or 17, according to the character of fuel used. During the gas making, or "run" period, the air valves 14 and 15, are closed, and steam is admitted through valves 16 or 17, or both, and passes up through the fire and through the open valve 19, into the offtake 22. When it is desired to reverse the gas making direction, valves 16, 17 and 19, are closed, steam is admitted through 18, and escapes either through the valve 20 or 21, into con-

nection 22, as desired. By means of the auxiliary valve 20, it is possible to further control location of the temperature zones 5 and 6, of the generator.

Referring to Fig. 3, the process is as above described and the blow consists in admitting air, which may be mixed with products of combustion, steam or the like, through valve 23, to the base of the fire, the products escaping through valve 25, and connection 28, or by admitting air mixed with products of combustion, steam, or the like, through 24, and allowing the products of combustion to pass out through valves 26 or 27, to connection 28. During the run, steam is admitted to 29, the resultant gas leaving through valve 25, and connection 28, or steam is admitted through valve 30, the products leaving through valves 26 or 27. By changing the direction of application of the gas making fluids, and by taking off the products at various points in the fuel bed, the location of the temperature zones 5 and 6, can be changed as desired.

In practising the process of the invention in connection with the apparatus illustrated in Figs. 1-3, a burning fuel-bed is fed through a furnace chamber in which there is created and maintained, for example, by the means described, near the furnace wall, a temperature zone where fused clinker solidifies, and the surfaces of the furnace wall and of the fuel bed are separated at this zone, so that the clinker of the fuel bed passing through this zone, solidifies out of contact with the furnace wall. This may be accomplished by properly proportioning the cross-sectional areas of the furnace and of the fuel-bed for separating the surfaces of the fuel-bed and of the furnace wall at the temperature zone of solidification of clinker in the passing fuel.

Due to high temperature existing at the region of the bosh, this bosh, unless protected, may be subjected to wear. The admission of blast directly below the bosh serves to protect it to some extent. In some cases, however, it is advisable to admit the blast to an annular passage 31, in the interior of the bosh, as shown in Figs. 4 and 5, the blast escaping through the ports 32. In other cases it may be advisable to water-cool a portion of this bosh in any of the well known ways. In the claim the term blast includes both pressure and suction application.

What I claim is:

The process of burning fuel which consists in feeding a burning fuel-bed through a furnace chamber, establishing and maintaining in the contents of said chamber in superposed relation an ash fusing region and a clinker solidifying and carbon burning

region by appropriate blast control, passing a combustible admixture or association of residue and carbon from the ash fusing region to the clinker solidifying and carbon burning region and separating the surfaces of the furnace wall and of the passing admixture or association by providing space at the furnace wall in the vicinity of the entrance to the ash solidifying and carbon consuming region, and thereafter burning the carbon out of the admixture in the clinker solidifying region, substantially as described.

OWEN BROOKE EVANS.
